(57) **CLAIM**

The ornamental design of a thermostat, as shown and described.

DESCRIPTION

FIG. 1 is a perspective view of an embodiment of a thermostat.

FIG. 2 is a front view of the embodiment shown in FIG. 1.

FIG. 3 is a rear view of the embodiment shown in FIG. 1.

FIG. 4 is a right side view of the embodiment shown in FIG. 1.

FIG. 5 is a left side view of the embodiment shown in FIG. 1.

FIG. 6 is a top view of the embodiment shown in FIG. 1; and,

FIG. 7 is a bottom side view of the embodiment shown in FIG. 1.

The broken lines in the Figures are for illustrative purposes only and form no part of the claimed design. The shade lines in the Figures show contour or the flatness of a surface, and not surface ornamentation.
